PRODUCTION OF KINKED CARPET YARN

Clyde W. Brown, Walter H. Crowder, and Eures C. Broach, Shawmut, Ala., assignors to West Point Manufacturing Company, West Point, Ga., a corporation of Georgia

Filed June 18, 1959, Ser. No. 821,226
9 Claims. (Cl. 28—72)

This invention relates to the production of carpet yarn, and in particular to the production of permanently kinked carpet yarn of synthetic fibers. A principal object of the invention is the production of highly and uniformly kinked yarn. Other objects are to provide efficient, controllable and reproducible procedures for the production of kinked carpet yarn of outstanding appearance and physical properties. Further objects will be in part evident and in part pointed out hereinafter.

The invention and the novel aspects thereof will be described in connection with the accompanying drawings, in which:

FIGURE 1 is a perspective view of an exemplary shaker mechanism, utilized in the present invention to facilitate the relaxation and kinking of skeins of twisted yarn;

FIGURE 2 is a side elevational view of the shaker mechanism of FIGURE 1;

FIGURE 3 is a detail view in perspective, on enlarged scale, illustrating the condition of a yarn skein after shaking;

FIGURE 4 is a side elevational view, partly in perspective, of a skein stretching mechanism useful in the process;

FIGURE 5 is a perspective view of the stretching mechanism of FIGURE 4, viewed from the front thereof, and showing a skein of yarn in position to be stretched;

FIGURE 6 is a detail view illustrating the lengthened condition of the yarn skein shown in FIGURE 5, after stretching;

FIGURE 7 is a perspective view of a swift useful for opening up and disentangling the stretched skeins, to facilitate winding the yarn onto bobbins;

FIGURE 8 is a perspective view of the swift of FIGURE 7, partly broken away, illustrating the swift in collapsed condition, and

FIGURE 9 is a perspective view of the swift, on reduced scale, in open condition with a skein of kinked yarn ready for unwinding therefrom.

In accordance with the present process, synthetic fibers may be initially carded and converted into roving on wool cards. By way of example, Acrilan fibers of 15 denier and 3 to 4" staple length, or nylon fibers, 6 and 15 denier and 3 to 4" staple length, may be employed. Acrilan and nylon fibers may be blended, if desired, and as will be evident, other thermoplastic synthetic fibers of similar or different properties, and blends thereof, may be employed as well. To even out bale to bale differences in color and quality, several bales are customarily blended together prior to carding by means of a conventional opening system.

The roving produced by the wool cards then goes through the usual spinning process, wherein it is drafted and twisted, and may be doubled. A suitable draft is 1.2. The single ends thus produced may be, for example, 2.75's yarn with a twist of 3.75 to 4 turns per inch (cotton count). Preferably, the ends are then piled into a 3-ply .92's yarn with a twist of about 7.2 turns per inch. The twist is excessive, whereby the yarn will tend to form kinks when the tension thereon is released.

The twisted yarn is produced on twisting frames and wound onto wooden bobbins, necessarily under such tension that the twisting stresses cannot relieve themselves,

2

to produce the desired kinking effect. To relieve the tension, accordingly, the twisted yarn is rewound from the bobbins into skeins. The yarn in skein form relaxes somewhat and forms a few kinks, but remains substantially in the form of a wavy bundle. It has been found that relaxation and kinking of the yarn at this stage of the process can be greatly promoted by brief but vigorous shaking of the skeins. Suitable mechanism for this purpose is illustrated in FIGURES 1 and 2 of the drawings.

10 As there shown, the shaker mechanism includes a base comprising parallel spaced members 2 adapted to rest on the floor of a building, joined at their ends by the angle bars 4 which may be welded or otherwise secured thereto. The flanges of the angle bars 4 may be attached to the floor by bolts 6, and brackets 8 affixed to the sides of the members 2 may be secured to the floor by bolts 10.

15 Adjacent an end of each base member 2, a bearing 12 is mounted thereon as by bolts 14, and an oscillating shaft 16 extends between the bearings and is journaled therein. Midway of the length of shaft 16 a post 18 extends upwardly therefrom, the post supporting two parallel and spaced skein carrying rods 20 and 22, by means of the horizontal link 24 extending between the rods and the brace 26 extending between the rod 22 and post 18. Each end of the rods 20 and 22 is provided with an upwardly extending stop pin 28, to retain skeins on the rods. As will be evident, the post 18 and the rods 20 and 22 mounted thereon constitute a shaker frame, oscillatable about the axis of shaft 16.

20 To oscillate the shaker frame, a connecting rod 30 extends from post 18 to an eccentric 32, mounted on one end of a shaft 34 which is journaled in the bearings 36 mounted on the supports 38, which in turn rest on one of the base members 2. The other end of shaft 34 carries 25 a pulley 40, which is engaged in driving relationship by a belt 42 to the electric motor 44. The connecting rod 30 is provided at its ends with the bearing heads 46 and 48, bearing head 46 being rotatably mounted on a pin 50 projecting laterally from the eccentric 32, and bearing head 48 being similarly mounted on a stub shaft 52 extending between the lugs 54 extending from the post 18. As will be evident, the motor 44 is adapted to drive shaft 34, and through the eccentric 32 and connecting rod 30 impart a reciprocatory, shaking movement to the 30 shaker frame, the extreme positions of which are illustrated in FIGURE 2.

For the shaking operation, a number of skeins 56 of twisted yarn are positioned on the rods 20 and 22, enough to loosely fill the lengths thereof between the stop pins 28. 35 In FIGURE 1 but two skeins are shown, their loose wavy form representing the appearance of the skeins prior to shaking. Motor 44 is then energized, and the skeins subjected to violent shaking for a brief period of time. A shaking frequency of about 450 cycles per minute has 40 proved satisfactory in practice, and a period of about 18 or 20 seconds is adequate for the purpose of the invention. The shaking operation effects marked relaxation and kinking of the yarn, the skeins assuming the highly kinked and irregular appearance illustrated in FIGURE 45 3. In the course of this kinking the skeins draw up to about one half their length prior to shaking.

The kinks so obtained in the yarn are not permanent, and if the yarn is cut into short lengths as may occur, for example, in the manufacture of cut pile tufted carpets, the kinks are prone to straighten out. Accordingly, the kinks are rendered permanent at this stage of the process by heat setting. To heat set nylon yarn, approximately 200 pounds of kinked skeins are loaded into a tumbler basket, and tumbled for a period of 30 minutes, whereby complete relaxation of the yarn is attained. The tumbler basket is then inserted into an autoclave, and the skeins

subjected to alternate cycles of vacuum and steam pressure, as follows:

- (a) Vacuum—5 min.—28" mercury
- (b) Steam—6 min.—245° F. 26 p.s.i.g'
- (c) Vacuum—½ min.—28" mercury
- (d) Steam—6 min.—245° F. 26 p.s.i.g.
- (e) Vacuum—6 min.—28" mercury

Acrilan yarn may be heat set in similar fashion, that is by initial tumbling followed by an alternating vacuum-steam pressure treatment of the nature described.

In the course of the heat setting operation, the skeins shrink together to such degree that they can be opened up for further processing only with great difficulty. In accordance with the present invention, the heat set skeins are mechanically stretched in simple and novel manner, to open up the skeins and facilitate further processing. The stretching operation, moreover, is found to improve the properties of the yarn. Mechanism suitable for the stretching operation is illustrated in FIGURES 4, 5 and 6 of the drawings.

In FIGURES 4 and 5, 76 represents a base or frame, composed of upright members 78 connected by horizontally disposed side members 80 and a front rack member 82. The uprights 78 at the back of the device extend above the upper side members 80, and mount between them a shaft 84 which extends beyond the uprights to form trunnions 86 on which bearings 88 are rotatably mounted. The bearings 88 support a pivotal rack 90, comprising rack arms 92 extending to the front of the machine and having extensions 94 extending rearwardly of the bearings.

The front ends of the rack arms 92 are connected by the upper rack member 100, which is provided with a plurality of appropriately spaced lugs 102 having arms 104 extending upwardly from the outer ends thereof. As clearly shown in FIGURE 5, the lower rack member 82 carries a plurality of similar lugs 102, corresponding in number and spacing to those on the upper rack member 100, and provided with similar but downwardly extending arms 104.

The pivotal rack 90 is illustrated in FIGURE 5 in lowermost position, from which it is adapted to be elevated to the position illustrated in FIGURE 4. For this purpose, an air cylinder 106 is engaged to the pivotal rack 90, and to the frame therebelow. As shown in FIGURE 4, the piston rod 108 of the air cylinder 106 may be provided with a forked connection 110, which is pivotally connected by a bolt 112 to an ear 114 extending from the lower side of the cross member 116, which extends between the rearward ends of the rack arm extensions 94. The lower end of the air cylinder 106 may be provided with a pair of spaced ears 118, pivotally connected by the bolt 120 to the bracket 122 appropriately mounted on the cross member 124 of the frame. Pressure air may be conducted to the air cylinder 106 in the usual manner, by means of flexible hoses 126 and 128.

With the stretching device in the position illustrated in FIGURE 5, heat set skeins are arranged over corresponding lugs 102 of the upper and lower rack members, as illustrated in the figure. When the racks are filled, the air cylinder is activated to pivot the rack 90 to the position illustrated in FIGURE 4, whereby the skeins are severely stretched in a single, smooth continuous stroke, extended over approximately 2 or 3 seconds. While the stretching may be effected stepwise, the procedure described is found to be most effective. On returning the rack 90 to the position of FIGURE 5, the skeins are found to have the appearance illustrated in FIGURE 6.

The heat set skeins, so stretched, may now be opened and straightened on swifts, and then unwound therefrom onto bobbins in conventional manner. This step completes the processing of the yarn, made ready thereby for manufacture into carpet. A swift particularly adapted to

facilitate the final winding operation is illustrated in FIGURES 7, 8, and 9 of the drawings.

As best shown in FIGURES 7 and 8, the exemplary swift includes a base plate 130, supporting an upright 132 which is surmounted by a plate 143. Aligned bearings 136 on the plate 134 rotatably mount a shaft 138, which is provided at one end with a pinion 140 enclosed within housing 142. On the other side of the bearings, a collar 144 is rotatable on the shaft 138. Four plates 146 extend radially from the collar 144, these plates being angularly spaced 90° apart as shown. A spaced pair of arms 148 is pivotally engaged to each plate 146 and extends outwardly therefrom, the outer ends of each pair of arms being similarly pivotally engaged to and joined by a skein support 150, in a parallelogram arrangement. The end 152 of shaft 138 extending beyond collar 144 is threaded, and a cruciform nut 154 is carried thereby and threadedly engaged thereto. A rigid link 156 extends between the nut 154 and each adjacent arm 148, each link being pivotally connected at both ends.

A short distance below the shaft 138 a parallel stub shaft 158 extends from the upright 132, the stub shaft mounting a gear 160 having an operating handle 162 fixedly secured thereto. The gear 160 is freely rotatable on stub shaft 158 and relatively axially movable thereon as well, whereby the gear 158 may be readily engaged with and disengaged from the pinion 140.

In FIGURE 7 the swift is illustrated in fully opened position, wherein the nut 154 adjoins the collar 144. To utilize the swift in the present process it must first be collapsed to the position of FIGURE 8. To accomplish this, the normally disengaged gear 160 is moved into meshing engagement with pinion 140. While restraining the arms 148 and supports 150 from turning, gear 160 is rotated in appropriate direction by means of its handle 162 to rotate the pinion 140 and shaft 138, and thereby cause the nut 154 to travel outwardly therewith, the nut being restrained from rotation by the links 156 connected to the arms 148. As the nut travels outwardly along the threaded end of the shaft 138, it acts through links 156 to deflect the arms 148 outwardly, thereby moving the supports 150 inwardly while maintaining them parallel to the shaft axis. The fully collapsed position of the swift is illustrated in FIGURE 8.

With the swift in collapsed position, a yarn skein processed as previously described may be readily positioned on the supports 150, and the swift may then be opened by reversing the procedure just described. That is, the gear 160 is rotated in the opposite direction while restraining the arms 148 and supports 150 from rotation, the resultant rotation of shaft 138 causing the restrained nut 154 to travel inwardly toward the collar 144, the movement of the nut pivoting the arms 148 by means of the links 156, whereby the supports 150 are spread outwardly to the position of FIGURE 9, the skein being opened thereby and disentangled. The gear 160 may then be disengaged from the pinion 140, leaving the swift free to rotate, whereupon the yarn may be unwound therefrom and wound onto bobbins with ease and efficiency.

It will thus be seen that there has been provided by this invention a method in which the various objects hereinbefore set forth, together with many practical advantages, are successfully achieved. As various possible embodiments may be made of the novel features of the above invention, all without departing from the scope thereof, it is to be understood that all matter hereinbefore set forth is to be interpreted as illustrative, and not in a limiting sense.

What is claimed is:

1. A process for producing kinked synthetic carpet yarn comprising the steps of twisting yarn, skeining the twisted yarn, shaking the yarn skeins in an oscillating fashion to facilitate relaxation and kinking of the yarn, and heat setting the yarn in relaxed and kinked state, stretch-

ing the heat set yarn, and then winding the yarn onto bobbins.

2. A process for producing kinked synthetic carpet yarn comprising the steps of twisting yarn, skeining the twisted yarn, shaking in an oscillating fashion the yarn skeins to facilitate relaxation and kinking of the yarn, heat setting the skeins in relaxed and kinked state, stretching the skeins, and then winding the yarn onto bobbins.

3. A process for producing kinked synthetic carpet yarn comprising the steps of twisting synthetic fiber yarn, skeining the twisted yarn to reduce the tension thereon and permit kinking, shaking the skeins in an oscillating fashion to facilitate further relaxation and kinking of the yarn, tumbling the skeins to complete relaxation of the yarn, heat setting the skeins in relaxed and kinked state to make the kinks permanent, stretching the heat set skeins, and then winding the skeins onto bobbins.

4. A process as defined in claim 3, wherein said yarn is multiple ply yarn.

5. A process as defined in claim 3, wherein said shaking is effected as a frequency of about 450 cycles per second, for a period of about 18 seconds.

6. A process as defined in claim 3, wherein said skeins are tumbled for a period of about 30 minutes.

7. A process for producing kinked synthetic carpet yarn comprising the steps of twisting the yarn, skeining the twisted yarn, shaking the yarn skeins to facilitate relaxation and kinking of the yarn, heat setting the skeins in relaxed and kinked state, and then stretching the skeins in a single, smooth, continuous stroke.

8. A process for producing kinked synthetic carpet yarn comprising the steps of twisting synthetic fiber yarn, skeining the twisted yarn to reduce the tension thereon and permit kinking, shaking the skein to facilitate further relaxation and kinking of the yarn, tumbling the skeins to complete relaxation of the yarn, heat setting the skeins in a relaxed and kinked state by alternate application of vacuum and pressure steam to make the kinks permanent, and then stretching the heat set skeins.

9. A process as defined in claim 3, wherein the skeins are maintained in open, stretched condition while winding the skeined yarn onto said bobbins.
